CLAIM

The ornamental design for a hose hanger, as shown and described.

DESCRIPTION

FIG. 1 is a front perspective view of the hose hanger of the instant invention;

FIG. 2 is a front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an exploded view thereof;

The broken lines in the drawings represent unclaimed environmental subject matter.
